UNITED STATES PATENT OFFICE.

RUDOLPH HOFFMAN, OF CHICAGO HEIGHTS, ILLINOIS.

DESIGN FOR A STOVE-SHELF.

47,463.

Specification for Design. Patented June 15, 1915.

Application filed March 22, 1915. Serial No. 16,294. Term of patent 14 years.

To all whom it may concern:

Be it known that I, RUDOLPH HOFFMAN, a citizen of the United States, residing at Chicago Heights, in the county of Cook and State of Illinois, have invented a new, original, and ornamental Design for Stove-Shelves, of which the following is a specification, reference being had to the accompanying drawing, forming part thereof.

Figure 1 is a perspective view of a stove

shelf showing my new design. Fig. 2 is a top plan view of the shelf. Fig. 3 is an end elevation of the shelf.

I claim:

The ornamental design for a stove shelf, as shown.

RUDOLPH HOFFMAN.

Witnesses:

GEORGE L. CHINDAHL,
MARGARET H. MANN.
